UNITED STATES PATENT OFFICE.

HAMILTON ABERT, OF PASSAIC, NEW JERSEY, ASSIGNOR TO THE MANHATTAN RUBBER MANUFACTURING COMPANY, OF PASSAIC, NEW JERSEY, A CORPORATION OF NEW JERSEY.

GOLF-TEE.

1,144,747.

Specification of Letters Patent. Patented June 29, 1915.

Application filed March 11, 1915. Serial No. 13,592.

To all whom it may concern:

Be it known that I, HAMILTON ABERT, a citizen of the United States, residing at Passaic, New Jersey, have invented certain 5 new and useful Improvements in Golf-Tees, of which the following is a clear, full, and exact description.

My invention relates to golf tees but more particularly to those which can be weighted 10 to the ground. Ordinarily golf tees are very light in weight, and for this reason it is difficult to hold the same in the exact position desired on the ground.

It is the object of my invention to ob- 15 viate this disadvantage by attaching to the tee a weight or anchor which is heavier than the tee proper and which is made up in suitable form and shape to readily hold its position on the ground adjacent to the tee, and 20 which is connected to the tee in such a manner that when the weight is moved about from place to place, it will carry the tee with it, always holding the latter in its up-right position.

25 A further object of the invention is to so connect the weight and tee that the latter will be normally rigid relatively to the weight but may yield in respect to the same, thereby enabling the device to be folded or 30 rolled up when not in use.

I attain these and other objects of my invention in the preferred embodiment thereof set forth in the following description and accompanying drawings, in which like reference characters refer to corresponding parts.

35 In the drawings, Figure 1 is a plan view of my device; Fig. 2, a side view thereof when partially folded, and Fig. 3 a longitudinal vertical section taken on the line X—X in Fig. 1.

40 My device generally consists of the tee 2 which may be of any suitable construction, but I prefer to shape the same in the form of a cup having a rim 3 on which the golf ball may rest. In order to provide a 45 cup of the proper shape and having the proper wall thickness, and at the same time to provide a base of suitable dimensions to support the cup, I preferably form a flange 3' about the base portion of the cup. At- 50 tached to one side of the cup 2 and projecting therefrom, is a bar 4 which is pref- 55 erably flattened so that it will lie below a horizontal plane passing across the top of

the cup and is preferably of substantially uniform width and substantially uniform thickness. Suitably attached to the outer extremity of the bar 4 is a weight or anchoring portion 5 which is also preferably flattened to have a substantial undersurface area so that it will readily retain its equilibrium on the ground. The device may be made out of any suitable material, but I prefer to mold the same in one piece out of resilient rubber or material having properties like rubber, it being particularly desirable that the connecting link or bar 4 should be made of this material in order that it may be folded so that the device can be readily 60 carried in the pocket of a garment. This material further has its advantages in that it is not breakable and is weather-proof. In fashioning my tee I find it advantageous to make the cup and bar out of a composition 65 which has a relatively light specific gravity and the weight or anchoring portion out of a composition which has a relatively heavy specific gravity. The feature of flattening the bar and weight so that all the parts may 70 lie flat upon the ground permits of a structure which is extremely neat and compact, which retains well its position on the ground and further in the case of the weight enables the device to be readily turned over on the 75 ground with the foot, should by chance the device become reversed. From the above description, other advantages will readily suggest themselves.

79 While I have illustrated and described the preferred embodiment of my invention, it should be distinctly understood that the same is susceptible to such modification as may fairly come within the scope of the ap- 85 pended claims.

89 What I claim is:—

1. A golf tee having a weight connected thereto by a link; all of said parts being formed out of resilient rubber as an integral structure. 95

2. A golf tee, a weight therefor, and a link connecting said tee and said weight, all formed integral of rubber and having a continuous flat undersurface. 100

3. A golf tee, a weight therefor, and a link of substantially uniform width and substantially uniform thickness connecting said tee and said weight, said tee, weight and link being all formed integral of rubber and having a continuous flat undersurface. 110

4. A golf tee, a weight therefor, an elastic link rigidly connected at its respective ends to said tee and said weight, said tee, link and weight presenting a continuous flat undersurface.

5. A golf tee, a weight therefor, and a link connecting said tee and said weight, all formed integral of rubber, the weight portion of said integral rubber structure being of a specific gravity higher than that of the tee portion.

6. A golf tee having a weight connected thereto by a link, the said tee, weight and link being molded into one integral structure and the said weight being made out of a composition of relatively greater specific gravity than the other parts.

7. A golf tee having a weight connected

thereto by a link, all of said parts being formed into an integral structure of resilient rubber and the material composing said weight being of relatively greater specific gravity than that composing the other parts.

8. A golf tee, a weight therefor, and a link connecting said tee and said weight, all formed integral of rubber and having a continuous flat undersurface, said tee being formed as a cup provided at its bottom with a flange having its undersurface continuous with that of the tee.

Signed at Passaic, New Jersey this 25th day of January 1915.

HAMILTON ABERT.
